ACTUATING MEANS FOR SIPHON-DIS-
CHARGE APPARATUS IN WATER FLUSH-
ING INSTALLATIONS

(Cl. 4—50)

This invention relates to actuating means for siphon-discharge apparatus with vertically movable siphon bell for delivering different quantities of water at will (large and small flush).

Actuating means for siphon-discharge apparatus with vertically movable siphon bell are already known which admit of delivering different quantities of water at will (for large and small flushing) by pulling down the conventional operating handle to different levels.

In accordance with the present invention there is employed for delivering one quantity of water (large flush), in the usual manner, the actuating means normally attached to the draw member 13 for lifting the siphon bell, and for delivering another quantity of water (small flush) a further actuating means which is likewise connected with the said draw member, and which is movably supported in a fixed housing which at the same time serves as a guide for the draw member. In order to preclude the possibility of mistaking the one actuating member for the other the manner of operating these two members is arranged to be different (e. g. in the one case by pulling and in the other by pushing). To enable the lift of the siphon bell to be adjusted as required, and that independently for the large flush and for the small flush, parts of the actuating mechanism are made adjustable. Further features of the invention relate to constructive details.

The invention is illustrated, by way of example, in the accompanying drawing, in which:

Fig. 1 shows in section a flushing cistern equipped with siphon-discharge apparatus fitted with actuating means according to the invention.

Figs. 2 and 3 show forms of construction of actuating means according to the invention, in section, on an enlarged scale.

Referring to Fig. 1 of the drawing, the flushing installation consists of a water tank 1, with an inlet or feed pipe 3 controlled by a float valve 2, and a discharge pipe 4 over which there is disposed a siphon bell 5 adapted to be lifted by means of a draw chain 6 and a fulcrumed lever 7. The siphon bell 5 is provided inside with an open section of tube 8 of which the lower end, provided with gasket elements 9, is seated in the manner of a valve upon the discharge pipe. The upper end 10 of the section of tube 8 is located so high up in the siphon bell that it is above the highest level reached by the water in the tank.

The actuating means for lifting the siphon bell 5 consists of a rod 14 which is connected by means of the sleeve 12 and ring 11 to the draw chain 6, and by means of the ring 22 to the handle

23, and which is guided in the housing 15 (Fig. 1). This housing is attached by means of bolts or the like 21 to the back plate 20 which is secured for example to a wall. In a slot in the rod 14 there engages the one arm of a bell-crank lever 19 which is pivoted at 18 in the housing 15, and of which the other arm is articulated to a stem extending out through the wall of the housing and fitted with a knob 17.

To effect the large flush the rod 14 is pulled down in the usual manner by means of the handle 23 so as to lift the bell of the siphon to such an extent that siphonic action is set up and the entire contents of the tank become discharged. To effect the small flush the knob 17 is pressed towards the housing, with the result that the rod 14 is pulled down to a less extent than when operated by means of the handle. The bell 9 of the siphon is then only slightly lifted, and water flows from the tank only as long as the knob is kept pressed in. When the knob or the handle is released the rod 14 returns to its position of rest in response to the action of the spring 24. By screwing the ring 11 in the sleeve 12 which is attached to the rod 14 by means of the screw 13 the draw chain may if desired or necessary be tightened up. The means provided for guiding the rod 14 also serve to guide the chain, and thus prevent the latter from becoming twisted.

In the form of construction shown in Fig. 2 the actuating knob 17 is of tubular shape and screwed on to a thrust stem 25 articulated to the bell-crank lever 19. By rotation and consequent adjustment of this knob the angle of pivotal movement of the bell-crank lever 19 co-acting with the rod 14, and therefor also of necessity the extent of the lift imparted to the siphon bell for effecting the small flush, is readjusted. The actuating knob 17 may be fixed in any desired position of adjustment by means of grub screws 26. These screws are suitably countersunk, as a precaution against unauthorized alteration of the lift of the siphon bell and consequently of the quantity of water discharged for the small flush. In order to provide for adjustment of the lift of the siphon bell for the large flush also, the handle 23 is connected by means of the ring 22 to a sleeve 27 guided in the casing 15, this sleeve being screwed on to the rod 14. The flange 27' on this sleeve serves as an abutment for limiting the movement of the rod 14 when the latter is pulled down. The adjustment of the lift of the siphon bell is effected by rotating the sleeve 27 which is then fixed in the desired position by means of countersunk set-screws 28. In order that the

press-in knob may be used for actuating the siphon-discharge apparatus for the delivery of the larger quantity of water, and the pull handle for the delivery of the smaller quantity of water 5 the rod 14 can be made to consist of two slidably interengaging or telescoped parts, namely a sleeve-like upper part 14a and a lower part 14b guided thereon; the lower part has a lateral aperture 14c in which there engages a correspondingly shaped lug 14d on the sleeve 14a. The lower part 14b is coupled to the upper part 14a in the direction of pulling, and is also locked against rotation. It is only on pulling down the handle 23 that the two parts 14a and 14b of the rod 14 are rigidly 10 connected together. The return movement of the draw rod 14 is effected or assisted by the springs 24 and 29. When the pressing-in knob is being operated the part 14a of the draw rod can also be moved on when the lower part 14b encounters 15 a resistance or obstruction.

In the form of construction shown in Fig. 3 of the drawing there is provided, instead of the push-in knob and bell-crank lever, a handle 30 which is connected to the rod 14 (portion 14a) 20 and which is guided in a slot 31 in the housing 15. In order to provide for adjustment of the stroke of the projecting handle 30 there is screwed on to the rod 14 a sleeve 32 which is guided in the housing, and which in its turn is connected, 25 through the intermediary of the ring 11, to the draw member for the siphon bell.

The device according to the invention has the particular advantage that it can readily be operated by anyone, while the siphon-discharge apparatus is saved from undue or unnecessary strain, and the draw chain prevented from becoming twisted. Since the actuating device is separate from the flushing apparatus proper it may be fitted to existing flushing installations.

40. I claim:

1. In a siphon-discharge apparatus a tank with an outlet, a siphon bell movable in said tank above the outlet, a draw rod for moving said siphon bell, the draw rod comprising two slidably interengaging parts coupled together for allowing limited relative axial movement of said parts, an actuating means attached to one of said parts, a further actuating means adapted to cooperate with the other of said parts, one of said actuating means being adapted for pulling down the draw rod to a greater extent than the other and thus to effect delivery of a larger quantity of water than the other actuating means, and a stationary housing for positively guiding the draw rod and for movably supporting said further actuating means.

2. In a siphon-discharge apparatus, a tank with an outlet, a siphon bell movable in said tank above the outlet, a draw rod for moving said siphon bell, the draw rod comprising two slidably interengaging parts coupled together for allowing limited relative axial movement of said parts, an actuating means attached to said draw member, a further actuating means adapted to cooperate with said draw member, one of said actuating means being adapted for pulling down the draw member to a greater extent than the other and thus to effect delivery of a larger quantity of water than the other actuating means, the said actuating means comprising relatively adjustable parts for adjusting the movement they impart to the draw rod and thus the lift of the siphon bell, and a stationary housing for positively guiding the draw rod and for movably supporting said further actuating means.

3. In a siphon discharge apparatus, a tank with an outlet, a siphon bell movable in said tank above the outlet, a draw rod for moving said siphon bell, the draw rod comprising two slidably interengaging parts coupled together for allowing limited relative axial movement of said parts, and further parts adapted to be screwed one into another and fixed in their relative positions for adjusting the length of the draw rod and thus the lift of the siphon bell, an actuating means attached to said draw rod, a further actuating means adapted to cooperate with said draw rod, one of said actuating means being adapted for pulling down the draw rod to a greater extent than the other and thus to effect delivery of a larger quantity of water than the other actuating means, and a stationary housing for positively guiding the draw rod and for movably supporting said further actuating means.

4. In a siphon-discharge apparatus a tank with an outlet, a siphon bell movable in said tank above the outlet, a draw rod for moving said siphon bell, the draw rod comprising two slidably interengaging parts coupled together for allowing limited relative axial movement of said parts, an actuating means attached to the draw rod, a further actuating means consisting of a bell crank lever pivoted at a fixed point and of a press-in knob mounted to one end of said bell crank lever, the other end of the latter being adapted to coat with said draw rod, one of said actuating means being adapted for pulling down the draw rod to a greater extent than the other and thus to effect delivery of a larger quantity of water than the other actuating means, and a stationary housing for positively guiding the draw rod, said housing being provided with said pivot of the bell crank lever.

5. In a siphon-discharge apparatus a tank with an outlet, a siphon bell movable in said tank above the outlet, a draw rod for moving said siphon bell, the draw rod comprising two slidably interengaging parts coupled together for allowing limited relative axial movement of said parts, an actuating means attached to said draw member, a further actuating means consisting of an arm rigidly attached to and laterally projecting from said draw rod, one of said actuating means being adapted for pulling down the draw rod to a greater extent than the other and thus to effect delivery of a larger quantity of water than the other actuating means, and a stationary housing for positively guiding the draw rod, said housing being provided with a slot, and said arm projecting through and being guided in said slot.

6. In a siphon-discharge apparatus, a tank with an outlet, a siphon bell movable in said tank above the outlet, a draw rod for moving said siphon bell, the draw rod comprising two slidably interengaging parts coupled together for allowing limited relative axial movement of said parts, an actuating means for said draw rod, a further actuating means adapted to cooperate with said draw rod, one of said actuating means, being adapted for pulling down the draw rod to a greater extent than the other and thus to effect delivery of a larger quantity of water than the other actuating means, a stationary housing for positively guiding the draw rod and for movably supporting said further actuating means, a sleeve movably guided in the housing and adjustably mounted to lower end of said draw rod, and a stop provided on said sleeve and adapted to cooperate with said housing for limiting the movement of the sleeve.

7. In a siphon-discharge apparatus, a tank with

an outlet, a siphon bell movable in said tank above the outlet, a draw member for moving said siphon bell, a draw rod comprising two slidably interengaging parts coupled together for allowing limited relative axial movement of said parts, a sleeve adjustably mounted to one end of the draw and fixed to said draw member, an actuating means attached to said draw rod, a further actuating means adapted to cooperate with said

draw rod, one of said actuating means being adapted for pulling down the draw rod to a greater extent than the other and thus to effect delivery of a larger quantity of water than the other actuating means and a stationary housing for movably supporting one of said actuating means and for positively guiding said draw rod and said sleeve. 5
